UNITED STATES PATENT OFFICE.

CHARLES F. HAKE, JR., OF CINCINNATI, OHIO.

MACHINE FOR MAKING BAIL-ATTACHING EARS FOR SHEET-METAL CANS.

1,250,306.

Specification of Letters Patent. Patented Dec. 18, 1917.

Application filed December 15, 1916. Serial No. 137,075.

To all whom it may concern:

Be it known that I, CHARLES F. HAKE, Jr., a citizen of the United States of America, and resident of Cincinnati, in the county of Hamilton and State of Ohio, have invented a new and useful Machine for Making Bail-Attaching Ears for Sheet-Metal Cans, of which the following is a specification.

10 In the usual method of manufacturing ears for sheet metal cans, the base and cap elements of the ears are assembled by hand, the bases being placed in rows in holders provided for them and the caps being placed 15 within the bases ready to be secured thereto, the caps and bases then being fed to a machine which performs the assembling operation. This method of construction necessitates the employment of a number of operatives 20 for the placing of the base and caps together in the holders provided for them, in order to keep the assembling machine busy in the operation of assembling the caps and bases. In order to attend to the 25 operation of the machine it is also necessary to employ an operative for this purpose. In addition to the expense entailed by having to employ many operatives for this simple detail of can construction, the operation of 30 placing the caps within the base consumes much time of an operative.

An object of my invention is to produce a machine for assembling the parts of the ears to which the bails of sheet metal cans 35 are attached, in such a manner that the employment of but one operative is necessary, the machine placing the caps within the bases of the ears and then securing them together, automatic means being provided 40 for feeding the elements to the machine and then discharging the completed ears therefrom.

This and other objects are attained in the machine described in the following specification and illustrated in the accompanying drawings, in which;

Figure 1 is a front elevation of a machine embodying my invention.

Fig. 2 is a plan view of the machine illustrated in Fig. 1.

Fig. 3 is a fragmental plan view of my ear assembling machine upon an enlarged scale.

Fig. 4 is a vertical section taken on the 55 line 4—4 of Fig. 3.

Fig. 5 is a vertical section taken on the line 5—5 of Fig. 1.

Fig. 6 is a fragmental vertical section taken on the line 6—6 of Fig. 1.

Fig. 7 is a fragmental vertical section 60 taken on the line 7—7 of Fig. 1.

Figs. 8 and 10 inclusive are enlarged sectional views of that portion of the machine shown in section and located between the lines 8—8 and 9—9 of Fig. 4. 65

Fig. 11 is an enlarged perspective view of an ear as assembled by the machine embodying my invention.

My ear assembling machine consists of a series of mechanisms, one mechanism which 70 is located to the left of the machine as disclosed in Figs. 1 and 3 inclusive, being employed for the purpose of feeding the bases of the ears to the assembling mechanism, another mechanism consisting of means for 75 feeding caps toward the assembling mechanism, the third mechanism being the assembling mechanism and the fourth mechanism being that employed for ejecting the assembled ears from the machine. 80

The mechanisms above referred to are mounted upon a frame 12, this frame being provided with a drive shaft 13 mounted in bearings 14 located at each end of the frame, the drive shaft being provided with a drive 85 pulley 15 and adapted to be connected with the drive shaft 13 by means of a clutch 16, the clutch being operated by hand lever 17 located at the side of the machine. Located beneath the table 17 of the frame 12 is a 90 shaft 18 extending in the same direction as drive shaft 13 and provided with a pulley 19 over which passes a belt 20 which communicates motion from a pulley 21 secured to the drive shaft. This shaft 18 is provided 95 with worms 22 and 23 which mesh with worm wheels 24 and 25 respectively, the worm wheels in turn being secured to vertically rotatable shafts 26 and 27 located in bearings 28 and 29 extending from the under 100 surface of table 17. The upper ends of shafts 26 and 27 are provided with turn table disks 30 and 31 which are employed for feeding the bases and caps to the assembling mechanism, turn table 30 being employed for 105 feeding the bases and turn table 31 being employed for feeding the caps, the former comprising a portion of the base feeding mechanism and the latter comprising a portion of the cap feeding mechanism. Located back of 110

table 17 and in substantially the same plane with drive shaft 13, is a shaft 32, parallel with shaft 13. Shaft 32 is provided with pulleys 33 and 34 over which pass belts 35 and 36 which communicate motion to pulleys 37 and 38 mounted on forwardly extending shafts 39 and 40. Drive shaft 13 is provided with a pulley 41 and shaft 32 with a pulley 42, which are operatively connected by means of a belt 43. Shafts 39 and 40 extend through hoppers 44 and 45 which communicate with the interior of drums 46 and 47 adapted to receive the bases and caps from the respective hoppers 44 and 45, drums 46 and 47 having selecting wheels 48 and 49 secured to shafts 39 and 40 respectively and adapted to receive bases and caps in the peripheries thereof and in proper position to feed them through ways 50 and 51, in the same manner that bottle caps are fed in bottle capping machinery, such as disclosed in Patent Number 643,973, issued Feb. 20, 1909 to Painter *et al.* Way 50 is adapted to receive the bases from the selecting wheel 48 of the drum 46 to bring them into position therein as disclosed in Figs. 1 and 2, way 51 communicating with selecting wheel 49 to locate the caps in the way as also disclosed in Figs. 1 and 2. Ways 50 and 51 are mounted on the table 17 and pass around the peripheries of the turn tables 30 and 31, the bottoms of the ways being removed at these points to permit the bases and caps to rest respectively upon the turn tables 30 and 31 and to be carried by them into position to be operated upon by the assembling mechanism.

Mounted on shaft 13 above turn table 30 is a cam 52, a roller 53 mounted on an arm 54 secured to a rock shaft 55, bearing upon cam 52. This cam is provided with a single lobe 52^a so that during a portion of its rotation the cam will cause rocking motion of lever 54 and consequent rocking motion of rock shaft 55. Shaft 55 is journaled in bearings 56 and 57 secured to the frame of the machine and adjacent to the center of the shaft a depending arm 58 is provided. This arm is connected adjacent to its lower end with one end of the spring 59, the opposite end of the spring being connected with a bracket 60 extending to the rear of the frame of the machine. The action of spring 59 is to cause roller 53 always to be held in engagement with cam 52 so that the roller will follow the contour of the cam during its rotation. The lower end of arm 58 is pivotally connected with a reciprocally mounted anvil 61, this anvil being mounted in a way 62 formed in the table 17. The forward end of the anvil is provided with a recess 61^a adapted to receive the bases of the ears as they are delivered thereto, an opening 63 being provided in the anvil immediately back of the recess 61^a, so that the

completed ears may be discharged there-through. Surrounding the turn tables 30 and 31 are plates 64 and 65 respectively, the inner ends of which form an abutment which removes the completed ears from the anvil upon forward reciprocation thereof and allows them to fall through the opening 63. An opening 66 is provided in the table immediately beneath opening 63 so that the ears will fall into a container placed beneath the machine for that purpose. In order to place the bases in position in recess 61^a of the anvil, I have provided a block 67 which is reciprocally mounted in a way 68 secured to a plate 69 attached to the table at the rear as disclosed in Figs. 2 and 3. This block 67 has a recess 70 formed therein, adapted to receive the bases as they are delivered thereto from the way 50. In order to reciprocate the block, an upwardly projecting pin 71 is provided, this pin pivotally mounting a link 72, the opposite end of which is connected with the forward end of a lever 73 mounted on plate 69 at a point to the rear of shaft 13. This lever is provided with a roller 74 adapted to ride upon the surface of a face cam 75 secured to shaft 13, the cam being so shaped as to give a dwell during a certain portion of the operation of the machine and at other portions of the operation to cause delivery of the base to the recess of the anvil. Arm 73 is connected with one end of a spring 76, the opposite end of which is connected with an arm 77 which is in all respects a duplicate of arm 73, and roller 78 like roller 74 being mounted on arm 77 for engagement with a cam 79 secured to shaft 13 and in all respects a duplicate of cam 75. The forward end of arm 77 is pivotally connected with a link 80, the opposite end of which is connected to a pin 81 extending upwardly from a block 82 reciprocally mounted in a way 83 secured to a plate 84 mounted on table 17 in the same manner that plate 69 is mounted thereon. Block 82 is provided with a recess 85 for receiving the caps delivered from way 51, said block in its reciprocation being designed to deliver the caps to the bases located in recess 61^a of anvil 61. Spring 76, permits of operation of either or both arms 73 and 77 and maintains their rollers 74 and 78 normally in engagement with their respective cams 75 and 79. The position of these cams on shaft 13 is such that cam 75 causes operation of arm 73 slightly in advance of the operation of cam 79 upon arm 77, so that the bases of the ears are positioned in recess 61^a previously to the delivery thereto of the caps by block 82. Cams 75 and 79 are provided respectively with humps 86 and 87 to cause operation of blocks 67 and 82 to deliver the bases and caps in position on the anvil, portions 88 and 89 being formed on the respective cams 130

for creating dwells or periods of inoperation of the blocks 67 and 82 during certain periods of operation of the machine.

A standard 90 is secured to the rear of table 17 and has an overhanging forward portion in which is mounted reciprocally a plunger 91 located immediately above opening 66 in the table. This plunger is provided at its lower end with a telescoping portion 92 retained in position therein and yieldingly mounted by means of a spring 93. The upper end of plunger 91 is screw threaded and is provided with adjustment nuts 94 and 95 between which a block 96 is located. This block has stub shafts 97 and 98 extending therefrom upon which links 99 and 100 are pivotally mounted, the lower ends of the links being pivotally connected with the forward ends of rocking levers 101 and 102, the opposite ends of the levers bearing rollers 103 which operate upon cams 104 and 105 secured to shaft 13. Each of the cams 104 and 105 is provided with a lobe 106 for causing rocking movement of levers 101 and 102 upon their pivots 107. Extending upwardly from standard 90 is a rod 108 which is provided with a plate 109 having two arms extending therefrom and connected with the upper ends of springs 110 and 111, the lower ends of which are connected with the stub shafts 97 and 98 of the block 96. These springs normally maintain rollers 103 in engagement with cams 104 and 105. The lower end of telescoping portion 92 and plunger 91 is recessed to the curvature of the caps against which it is brought to bear during the assembling operation, the periphery of the telescoping portion bearing against the rim of the cap in forcing it into position within its base.

The bases and caps to be assembled are placed in the respective hoppers 44 and 45, thence entering the drums 46 and 47 to be distributed therefrom and placed in the respective ways 50 and 51, sliding down the vertical portions of these ways to the inclined portions and then into the horizontal portions through which they are carried by means of the respective turn tables 50 and 51 to the assembling mechanism. Owing to the position of cam 75 slightly ahead of cam 79, arm 73 is operated to retract block 67 and to permit of the entrance of one of the bases into recess 70 of the block. Following this operation closely, cam 79 causes movement of arm 77 and consequent retraction of block 82 to permit of the entrance into recess 85 thereof, of one of the caps located in way 51. During this retracting movement of block 82, block 67 has started on its transverse motion toward anvil 61 which is in position to receive the base delivered thereby into its recess 61^a. Immediately upon delivery of the base to recess 61^a, the cooperating cap is delivered by block 82 as disclosed in Fig. 9, and during the movements of blocks 67 and 82 toward one another, the bases and caps which engage these respective members, are prevented from movement until the members are again fully retracted to receive fresh bases and caps. Humps 89 and 87 of respective cams 75 and 79 come into engagement with rollers 74 and 78 and cause retraction of blocks 67 and 82, thus leaving the superimposed base and cap free to be operated upon by plunger 91. During this time anvil-operating cam 52 is in such a position that roller 53 which bears against it, is away from cam lobe 52^a. This permits of the anvil remaining stationary during operation of plunger 91, lobes 106 of cams 104 and 105, now coming into operation to cause reciprocation of levers 101 and 102 so as to force plunger 91 downwardly. Downward movement of plunger 91 brings its telescoping portion 92 into engagement with the cap and causes this portion to yield to permit of self centering adjustment of the cap and base with relation to each other and to the recess, until the tension of spring 93 is sufficient to force the cap within the base as disclosed in Fig. 10, the base being formed with a restricted opening for reception of its co-operating cap. The cap having been pressed into position within its base, the plunger is withdrawn by reason of movement of lobes 106 away from rollers 103, springs 110 and 111 lifting the plunger. Simultaneously with this operation lobe 52^a of cam 52 engages roller 53 of arm 54 and through arm 58 causes reciprocation of the anvil and consequent discharge of the assembled ear from the recess 61^a by reason of its engagement with plates 64 and 65, the assembled ear falling through opening 63 of anvil 61 and into the receptacle provided for it. During movement of plunger 91 away from anvil 61, and before anvil 61 has returned to its normal base and cap-receiving position, blocks 67 and 82 have been retracted, have received another base and another cap in their respective recesses 70 and 85 and are again moving toward the anvil to place the base and cap carried thereby into position within recess 61^a ready for another assembling operation of the plunger. This operation is repeated as long as the machine is in motion, the only attention required being that of filling the hoppers 44 and 45 and of removing the full receptacles.

Having thus described my invention, what I claim is:

1. In combination in an ear assembling machine, a base feeding mechanism, a cap feeding mechanism, and an assembling mechanism, said base feeding mechanism comprising a way adapted to direct bases to said assembling mechanism, and a se-

lecting device adapted properly to place the bases in the way, said cap feeding mechanism comprising a way adapted to direct the caps to said assembling mechanism, and a 5 selecting device adapted properly to place caps in the way.

2. In combination in an ear assembling machine a base feeding mechanism, a cap feeding mechanism, said base feeding mechanism comprising a way adapted to direct bases to said assembling mechanism, and a selecting device adapted properly to place the bases in the way, said cap feeding mechanism comprising a way adapted to direct the 10 caps to said assembling mechanism, and a selecting device adapted properly to place the caps in the way, and said assembling mechanism comprising means for placing the caps within the base and a die adapted 15 to press the caps into locking engagement with the base.

3. In an ear assembling machine the combination of a base feeding mechanism, a cap feeding mechanism, and assembling mechanism adapted to place the caps within the bases and to secure them therein, and an ejecting mechanism adapted to remove the assembled ears from the machine, said ejecting mechanism consisting of a plate, and an 20 anvil reciprocally mounted adjacent to the plate, adapted to receive the bases and caps, to be held stationary during the assembling operation of the bases and caps, and to be moved to remove the assembled ears therefrom after completion of said assembling 25 operation, by bringing the ears into engagement with the plate.

4. In combination in an ear assembling machine, a base feeding mechanism, a cap feeding mechanism, an assembling mechanism, and an ejecting mechanism adapted to remove assembled ears from the machine, said base feeding mechanism comprising a way adapted to direct bases to said assembling mechanism, and a selecting device 40 adapted properly to place the bases in the way, said cap feeding mechanism comprising a way adapted to direct caps to said assembling mechanism, and a selecting device 45 adapted properly to place the bases in the way, said cap feeding mechanism comprising a way adapted to direct caps to said assembling mechanism, and a selecting device 50 adapted properly to place the caps in the way, said ejecting mechanism consisting of a plate, and an anvil reciprocally mounted adjacent to the plate, adapted to receive the bases and caps, to be held stationary during 55 the assembling operation of said bases and caps, and to be moved to remove the assembled ears therefrom after completion of said assembling operation, by bringing the ears into engagement with the plate.

60 5. An ear assembling machine comprising a base feeding mechanism, a cap feeding mechanism, and assembling mechanism adapted to place the caps within the base and to secure them therein, and an ejecting 65 mechanism adapted to remove assembled

cars from the machine, said assembling mechanism consisting of means for placing the caps within the base, and a die adapted to press the caps into locking engagement with the base, and said ejecting mechanism 70 consisting of a plate, and an anvil reciprocally mounted adjacent to the plate, adapted to receive the bases and caps, to be held stationary during the assembling operation of said bases and caps, and to be moved to remove the assembled ears from said anvil after completion of said assembling operation, by bringing the ears into engagement with the plate.

6. In combination in an ear assembling 80 machine, a base feeding mechanism consisting of a way adapted to direct bases to said assembling mechanism, and a selecting device adapted properly to place the bases in the way, a cap feeding mechanism 85 consisting of a way adapted to direct caps to said assembling mechanism, and a selecting device adapted properly to place the caps in the way, an assembling mechanism consisting of means for placing the caps within 90 the bases, and a die adapted to press the caps into locking engagement with the bases, and an ejecting mechanism consisting of a plate, and an anvil reciprocally mounted adjacent to the plate, adapted to receive the bases and 95 caps, to be held stationary during the assembling operation of said bases and caps, and to be moved to remove the assembled ears therefrom after completion of said assembling operation, by bringing the ears 100 into engagement with the plate.

7. An ear assembling machine comprising an assembling mechanism, means for feeding the bases and caps of ears to be assembled to the assembling mechanism, and an ejecting 105 mechanism adapted to remove the assembled ears from the machine, said ejecting mechanism consisting of a plate, and an anvil reciprocally mounted adjacent to the plate, adapted to receive the bases and caps, to be held stationary during the assembling operation of the bases and caps, and to be moved to remove the assembled ears therefrom after completion of said assembling operation by bringing the ears into engagement with the 110 plate, said assembling mechanism consisting of means for placing the caps within the bases upon the anvil, and a die adapted to secure the caps in locking engagement with the bases.

8. An ear assembling machine comprising a base feeding mechanism, a cap feeding mechanism, and an assembling mechanism adapted to place the caps within the bases and to secure them therein, said base feeding mechanism consisting of a continuously 125 moving turn table adapted to deliver bases to the assembling mechanism, and means adapted to deliver the bases to the turn table, said assembling mechanism being 130

adapted to stop the movement of the bases with said turn table during the assembling operation of the assembling mechanism, and to release the bases to permit movement 5 thereof by the turn table into position to be operated upon by the assembling mechanism upon completion of a previous assembling operation of the assembling mechanism.

9. An ear assembling machine comprising 10 a base feeding mechanism, a cap feeding mechanism, and an assembling mechanism adapted to place the caps within the bases and to secure them therein, said cap feeding mechanism consisting of a continuously 15 moving turn table adapted to deliver caps to the assembling mechanism, and means adapted to deliver the caps to the turn table, said assembling mechanism being adapted to stop the movement of the caps with said turn 20 table during the assembling operation of the assembling mechanism, and to release the caps to permit movement thereof by the turn table into position to be operated upon by the assembling mechanism upon completion 25 of a previous assembling operation of the assembling mechanism.

10. An ear assembling machine comprising 30 a base feeding mechanism, a cap feeding mechanism, and an assembling mechanism adapted to place the caps within the bases and to secure them therein, said base feeding mechanism consisting of a continuously 35 moving turn table adapted to deliver bases to the assembling mechanism, and means adapted to deliver bases to the turn table, said cap feeding mechanism consisting of a continuously moving turn table adapted to deliver caps to the assembling mechanism, and means adapted to deliver caps to the 40 turn table, said assembling mechanism being adapted to stop the movement of the bases and caps with said tables during the assembling operation of the assembling mechanism, and to release the bases and caps 45 to permit movement thereof by the turn tables into position to be operated upon by the assembling mechanism upon completion of a previous assembling operation of the assembling mechanism.

50 11. In an ear assembling machine the combination of a base feeding mechanism consisting of a continuously moving turn table adapted to deliver bases to the assembling mechanism, and means adapted to deliver 55 bases to the turn table, and a cap feeding mechanism consisting of a continuously

moving turn table adapted to deliver caps to the assembling mechanism, and means adapted to deliver caps to the second mentioned turn table, an assembling mechanism 60 adapted to place the caps within the bases, to secure them therein and adapted to stop the movement of the bases and caps with said first and second mentioned tables during the assembling operation of the assembling mechanism and to release the bases and caps to permit movement thereof by the turn tables into position to be operated upon by the assembling mechanism upon completion of 70 the assembling mechanism, and an ejecting mechanism adapted to remove the assembled ears from the machine.

12. In an ear assembling machine the combination of a base feeding mechanism consisting of a continuously moving turn table adapted to deliver bases to an assembling mechanism, and means adapted to deliver the bases to the turn table, a cap feeding mechanism consisting of a continuously 80 moving turn table adapted to deliver caps to an assembling mechanism, and means adapted to deliver caps to the second mentioned turn table, an assembling mechanism adapted to place the caps within the bases, 85 to secure them therein and adapted to stop the movement of the bases and caps with said turn tables during the assembling operation of the assembling mechanism and to release the bases and caps to permit movement 90 thereof by the turn tables into position to be operated upon by the assembling mechanism upon completion of a previous assembling operation of the assembling mechanism, and an ejecting mechanism 95 adapted to remove the assembled ears from the machine, consisting of a plate, and an anvil reciprocally mounted adjacent to the plate, adapted to receive the bases and caps, to be held stationary during the assembling 100 operation of the assembling mechanism and to be moved to remove the assembled ears therefrom after completion of said assembling operation, by bringing the ears into engagement with the plate.

In testimony whereof, I have hereunto subscribed my name this 13th day of December, 1916.

CHARLES F. HAKE, JR.
